US0D1029246S

(12) **United States Design Patent** (10) **Patent No.:** **US D1,029,246 S**
(45) **Date of Patent:** ** *May 28, 2024

(54) **MEDICAL CONNECTOR SEAL**

(71) Applicant: **ICU Medical, Inc.**, San Clemente, CA (US)

(72) Inventor: **Thomas F. Fangrow**, Mission Viejo, CA (US)

(73) Assignee: **ICU Medical, Inc.**, San Clemente, CA (US)

(*) Notice: This patent is subject to a terminal disclaimer.

(**) Term: **15 Years**

(21) Appl. No.: **29/925,516**

(22) Filed: **Jan. 24, 2024**

Related U.S. Application Data

(63) Continuation of application No. 18/123,181, filed on Mar. 17, 2023, now Pat. No. 11,896,795, which is a continuation of application No. 17/121,226, filed on Dec. 14, 2020, now Pat. No. 11,931,539, which is a continuation of application No. 16/412,326, filed on May 14, 2019, now Pat. No. 11,376,411, which is a continuation of application No. 15/828,317, filed on Nov. 30, 2017, now Pat. No. 10,391,293, which is a continuation of application No. 14/977,550, filed on Dec. 21, 2015, now Pat. No. 10,086,188, which is a continuation of application No. 13/857,019, filed on Apr. 4, 2013, now Pat. No. 9,278,206, which is a continuation of application No. 12/730,074, filed on Mar. 23, 2010, now Pat. No. 8,454,579.

CLAIM

The ornamental design for a medical connector seal, as shown and described.

DESCRIPTION

FIG. 1 illustrates a top perspective view of a medical connector seal; and,

FIG. 2 illustrates a bottom perspective view of the medical connector seal of FIG. 1.

The broken lines shown in the drawings illustrate portions of the medical connector seal that form no part of the claimed design.
